WILLIAM D. MARTIN AND DAVID T. BJORK, OF CHICAGO, ILLINOIS.

COLLECTION-RECEPTACLE.

1,183,095.

Specification of Letters Patent. Patented May 16, 1916.

Application filed February 26, 1915. Serial No. 10,664.

To all whom it may concern:

Be it known that we, WILLIAM D. MARTIN and DAVID T. BJORK, citizens of the United States, and residents of Chicago, in the county of Cook and State of Illinois, have invented certain new and useful Improvements in Collection-Receptacles; and we do hereby declare that the following is a full, clear, and exact description thereof, reference being had to the accompanying drawings, and to the letters of reference marked, thereon, which form a part of this specification.

This invention relates to collection receptacles, of that type adapted to be inset and secured in walls of buildings, of houses, apartments and the like, and designed to receive packages or articles of merchandise or the like. Receptacles of the kind referred to have entrance and exit openings, which are closed by suitable doors, the latter being opened when a package or article is placed into and removed from the receptacle. The entrance opening permits the package or article to be placed in the receptacle from the outside of the building wall, and the exit opening enables the deposited article to be removed from the receptacle from the inside of the wall or room of which the wall forms a part.

Among the objects of the invention is to improve the construction of a collection receptacle of the type referred to in the several particulars as will hereinafter appear, and to provide in particular means whereby the door of the entrance opening will be locked as soon as it is closed, after an article or articles are deposited in the receptacle, and will be held in locked position as long as such articles remain in the receptacle, and further to unlock the door as soon as the deposited article or articles are removed from the receptacle.

In its general features, a collection receptacle embodying the features of our invention comprises an entrance opening in its front wall, which, when the receptacle is inserted in the wall of a building, is located along the outer or exterior face of said wall, and an exit opening in its rear wall, which is located along the inner face of said wall and faces into the room or other compartment formed in part by said wall. A false bottom is located in said receptacle, and said false bottom is yieldably held above the bottom wall of the same. The entrance open-

ing in the front wall of the receptacle is closed by a door, which when opened permits a package or article to be deposited in the receptacle upon the false bottom wall 60 thereof. The weight of the article acts to depress said false bottom wall, and when the entrance door is closed the same is locked in such position. The entrance door is locked in closed position as long as the 65 package or article remains in the receptacle and access to the same from the outside of the building wall is prevented. The exit opening in the rear wall is closed by a door, which opens into the room of the house or 70 apartment, and when opened from the inside of the room enables the occupant of the same to remove the package that has been placed in said receptacle. As soon as the package is removed, the entrance door is 75 unlocked and may be opened to enable other articles to be deposited in said receptacle.

The invention consists further in the matters hereinafter described and more particularly pointed out in the appended claims. 80

In the accompanying drawings Figure 1 is a perspective view and in front elevation of a collection receptacle constructed in accordance with our invention, the receptacle being shown in the position it occupies when 85 inset in the wall of a building or the like; Fig. 2 is a perspective view and in rear elevation of said receptacle when inset in the wall of the building, the rear door of said receptacle being shown in open position; 90 Fig. 3 is a longitudinal sectional view, taken on line 3-3 of Fig. 2; Fig. 4 is a transverse, vertical sectional view, taken on line 4-4 of Fig. 3; Fig. 5 is a transverse, vertical sectional view, taken on line 5-5 of Fig. 3; 95 Fig. 6 is an enlarged, vertical sectional view, taken through the sliding front door of the receptacle, said sliding door being shown locked in its closed position; Fig. 7 is an enlarged, vertical sectional view of the same 100 parts shown in Fig. 6 and looking at such parts from the rear, the parts forming the latch device for said sliding door being shown in locked position in full lines and in unlocked position in dotted lines; Fig. 8 105 is an enlarged horizontal sectional view, taken on line 8-8 of Fig. 4; Fig. 9 is an enlarged, fragmentary, rear elevational view of the parts shown in Fig. 8; and Fig. 10 is an enlarged, fragmentary, vertical sectional view, taken on line 10-10 of Fig. 5. 110

Referring to the drawings, illustrating in

2

detail a collection receptacle or box constructed in accordance with our invention, 10 indicates the wall of a building, in which said receptacle is adapted to be inset. As shown, said receptacle is rectilinear in form, and comprises a front wall 11, a rear wall 12, and walls 13, 13, a top wall 14, and a bottom wall 15. The receptacle is preferably made of metal, and the walls thereof are rigidly joined to each other. 10 The interior space of the receptacle constitutes the package or merchandise-receiving compartment thereof, and, as illustrated, such compartment is divided into two chambers 16, 17 by a transverse partition wall 18, vertically arranged in the receptacle and secured to the top, bottom front and rear walls thereof. Said partition wall 18 is so located that the chamber 17 is considerably 15 larger longitudinally than the chamber 16. 20 The receptacle or box is made of such size as to completely fill the opening in the building wall, in which it is inset, and the front wall 11 of the receptacle is substantially 25 flush with the exterior face of said wall 10. The rear wall 12 of said receptacle is substantially flush with the rear face of said wall. The front wall 11 is provided with two doorways or openings, 19, 20, the latter 30 opening into the chamber 16, and the former opening into the chamber 17. Said openings 19, 20 constitute entrance openings for the receptacle, and through which the packages or other articles are passed in placing the same in said chambers 16, 17. 35 The opening 19 is opened and closed by a door 21, which, as shown, is of the sliding type, and is mounted in the chamber 17 so as to be moved endwise thereof over the 40 doorway 19 in opening and closing the same. Said door 21 is larger than said opening 19, and is slidably applied against the rear face of the front wall 11. Said door 21, when moved endwise toward the 45 partition wall 18, uncovers the entrance opening 19, and, when moved in the opposite direction, completely closes said opening 19. Said door 21 is slidably mounted in the chamber 17 in the following manner: 50 Located in the chamber 17 and secured to the top wall 14, adjacent the front wall 11, is an angle bar 22 which extends preferably the full length of the chamber 17. The upper portion of the sliding door 21 extends 55 into the space between the angle bar 22 and the front wall 11, as shown in Figs. 3, 5 and 6, and said door 21 is provided with rollers 23, 23 which have rolling contact with the upper face of a track portion 24, formed by a laterally projecting flange on 60 said angle bar 22. Said rollers 23, 23 support the door 21, and enable the same to be easily moved endwise in opening and closing the doorway 19. Located within 65 the chamber 17 and secured to the bottom wall 15, adjacent the front wall 11, is an angle bar 25, the upright flange 26 of which is arranged parallel to, but spaced inwardly from, said front wall 11. (See Figs. 5 and 6.) The upper margin of the flange 26 is 70 below the lower margin of the doorway opening 19. The angle bar 25 extends substantially the full length of the chamber 17, and the upright flange 26 thereof is provided, intermediate its ends, with a slot or 75 locking notch 27 opening upwardly through the upper edge of said upright flange 26. Said locking notch 27 is located opposite the doorway opening 19, and the opposed upper edges of said notch 27 are inclined upwardly 80 and outwardly, so as to give the entrance end of the slot 27 a flared shape, as shown in Fig. 7. Pivoted secured to the inner face of the sliding door 21, is a locking or latch member 28. The latter is pivoted to 85 the door 21 by a pivot pin 29, located above the center of the locking member, so that the same normally tends to swing into a vertical or upright position by reason of its gravity. The lower end of the latch member 90 28 rides on the upper margin of the flange 26 in the endwise movement of the door 21 into open and closed positions, and, when the door is moved into closed position, the lower end of the latch member is 95 adapted to drop into said locking notch 27. When the lower end of said latch member 28 drops into said locking notch 27, the latch member contacts with one of the side margins of said notch and holds the door 100 21 against endwise movement in a direction to open the same.

Located within the chamber 17, is a flat metal plate 30, which fits loosely within said chamber and forms the false bottom 105 thereof. Said plate 30 is provided along its front and rear margins with depending marginal flanges 32, 31, the latter being provided intermediate its ends with downwardly opening, vertical slots or notches 33, 33, adapted to receive inwardly projecting lugs or screws 34, 34 on the rear wall 12. (See Fig. 10.) Said parts 34, 34 are adjacent the bottom wall 15 of the receptacle and serve to hold the rear margin of the 115 plate 30 above said bottom wall 15. The front marginal portion of the plate 30 is normally held above said bottom wall 15 by means of a spring 35, located beneath said plate 30 and bearing upwardly thereagainst. As shown in the drawings, said spring 35 is of the leaf type and has its central depressed portion rigidly secured to the bottom wall 15 by fastening screws or rivets 36, 36. The opposite ends of the 120 spring 35 are spaced above the bottom wall 15 and bear upwardly against the bottom of the plate 30. The parts 34, 34 and spring 35 serve to hold the plate 30 normally in a substantially horizontal position and verti- 125 130

ally spaced above the bottom wall 15. Said plate 30 is in effect pivoted along its inner margin to the rear wall of the receptacle, its front margin being yieldably held 5 above the bottom wall 15.

In order to hold the lower or locking end 10 of the latch member 28 out of the locking notch 27, when the door 21 is closed and the chamber or compartment 17 is empty, so that the door 21 may be readily opened, we provide the following construction: The plate 30 is provided on its front margin with an outwardly projecting lug 37 (see Figs. 6 and 7), the latter being so positioned 15 as to extend into the locking slot 27. When the chamber 17 is empty, the plate 30 is maintained by said spring 35 in its normal position, as shown in Fig. 6, and the lug 37 is substantially flush with the upper margin 20 of the flange 26, as shown in dotted lines in Fig. 7, thereby preventing the lower end of the latch member 28 from dropping into the locking notch 27 when the door 21 is closed. When the chamber 17 is empty, the parts are 25 in the position shown in Fig. 3, and the door 21 is unlocked and may be moved endwise to open and close the opening 19. The door 21 is provided on its outer face with a handle 21^a, by means of which the door may be 30 moved endwise. Said door 21 is normally maintained in its closed position by a spring 21^b, one end of which is secured to the door and the other end of which is secured to one of the walls of the receptacle. (Fig. 3). Said spring 21^b extends across the door, as 35 shown in Fig. 3, and serves to normally hold the door closed. When the door 21 is moved into open position, the spring 21^b is expanded and acts to pull the door closed when 40 the same is released.

The rear wall 12 of the receptacle or box is provided with an exit opening 38 which opens into the chambers 16 and 17. Said exit opening 38 is closed by a door 39, which 45 has hinged connection with one of the margins of said door opening 38. As illustrated, said door 39 has hinged connection along its lower margin, by means of hinges 40, 40, with the rear wall 12, the hinges being 50 exteriorly applied against such parts. The door 39 is held in closed position by a suitable latch device, which, as shown in the drawings, comprises a handle 41 pivotally mounted on the outer face of the door 55 adjacent the upper margin thereof, and a keeper 42 fixed to the rear wall 12 of the receptacle. Said handle 41 is provided with a locking lug adapted in turning said handle to be moved into and out of locking 60 engagement with said keeper. The door opening 38 also opens into the smaller or second chamber 16, and the door 39 constitutes the closure therefor in the rear wall of the receptacle.

65 The chamber or compartment 17 is of

such size or dimensions as to receive rather large packages or parcels, such as laundry packages, boxes containing groceries, packages of merchandise and the like. When the chamber 17 is empty, the latch member 28 is held out of the locking notch 27, and the sliding door 21 may be moved to open the opening 19. The bottom plate 30 is in its normal position. When the door 21 is opened, a package or other article is inserted through the open doorway 19 and placed within the chamber 17 upon the bottom plate 30. The door 21 is then released and under the action of the spring 21^b is moved into closed position and completely 70 covers the door opening 19. The weight of the package or article in the chamber 17 depresses the bottom plate 30 against the spring 35, and consequently moves the lug 37 downward into the position shown in 75 full lines in Fig. 7. The lower end of the latch member 28 drops into the locking notch 27 as soon as the door 21 is closed. In this position of the parts, the lower end 80 of the latch member contacts with one of the side margins of the notch 27, and the door 21 is held or locked against endwise movement. The door remains locked as long as the article or articles remain in the chamber 85 17. Upon opening the door 39 at the back 90 of the receptacle, the articles may be removed from the chamber or compartment 17. As soon as the articles are removed from the chamber 17, the weight on the bottom plate 30 is relieved, and the latter under the action of the spring 35 is moved upward into its normal position. The lug or finger 37 is raised upward in the locking slot 27 and acts to raise the end of the latch member 28 out of said notch. The door 21 95 is thus unlocked and may be moved to open the opening 19 when another article or package is to be deposited in the receptacle. When several articles or packages are to be placed in the receptacle at one time, the door 21 is held open and the articles or packages placed in the chamber 17 in succession. As soon as the last article is placed 100 in the chamber 17, the door 21 is released, and the same is closed by the spring 21^b. 105

The chamber 16 is preferably smaller in transverse dimensions than the chamber or compartment 17, and said compartment 16 is designed to receive small articles, such as filled bottles of milk. Located in said chamber 16 is a false bottom 43, in the form of a flat plate, which is provided on its front and rear margins with depending marginal flanges 44, 44, the latter being provided intermediate its ends with vertical notches or 110 slots 46, 46, adapted to receive inwardly projecting lugs or screws 47, 47. The latter are arranged adjacent, but above, the bottom wall 15, and serve to hold the rear portion 115 of the false bottom plate 43 above the bot- 120

4

tom 15 of the box and in substantially the same plane with the lower margin of the rear door opening 38. The parts 47 and the slots 46 are made substantially the same 5 as the corresponding parts 33, 34, as shown in Fig. 10, and serve the same purpose. A spring 48 (see Fig. 4), located between the plate 43 and the bottom wall 15 and adjacent the front wall 11, serves to yieldably 10 maintain or hold the forward marginal portion of the bottom plate 43 in horizontal position and above and vertically spaced from the bottom wall 15. As shown in the drawings (Fig. 4), the spring 48 is of the leaf type, and has one end secured to the under side of said bottom plate 43. The free end of the spring 48 bears downwardly against the bottom wall. The parts 47, 47 and the spring 48 serve to normally hold the 15 bottom plate 43 above the bottom wall 15 in a substantially horizontal position. The doorway opening 20 in the front wall 11 of the receptacle opens into the chamber 16, and double doors 49, 49, of the swinging 20 type, are provided to close said doorway 20. Said double doors 49, 49 combined are larger than the opening 20, and each door is made exactly alike. Said doors 49, 49 are located in the chamber 16, and, when in position closing the opening 20, said doors are in lateral alinement and overlap the margins of the opening 20. Said doors 49, 49 are hung in the following manner: Secured to the inner face of the front wall 11, and 25 above each door 49, is a bracket 50. Secured to the inner face of each door 49, adjacent the lower margin thereof and in vertical alinement with the associated bracket 50, is a bracket 50^a. Said brackets 50, 50^a are 30 arranged at the sides of the door opening 20. Extending between each set of brackets 50, 50^a, is a rod 51, 51, about which is encircled a coiled spring 53, one end of which is secured to the door 49, and the other end 35 to the front wall 11. Said springs 53, 53 yieldably hold the doors 49, 49 in a position closing the entrance opening 20. The doors 49, 49 swing open in unison upon an article being forced inwardly thereagainst, 40 and, as soon as the article enters the chamber 16 and passes the doors, the latter, under the action of the springs 53, 53, spring into closed position, thereby closing the opening 20.

45 To hold the doors 49, 49 closed, when an article or articles are located in the chamber 16, a latch device of the following construction is employed: Secured to the inner face of the front wall 11, below the lower margin 50 of the entrance opening 20, is an angle bar 52, the flange 54 of which is horizontally disposed and extends inwardly from said front wall 11. The vertical flange 55 of said angle bar 52 is secured to the front wall 55 11. The angle bar 52 extends across the

chamber 16, but is below the doors 49, 49. Pivotally secured to the vertical flange 55, below the horizontal flange 54, are two locking dogs or catches 56, 56, one for each door 49, 49. (See Fig. 8.) The flange 54 is provided with slots 57, 57, one for each locking dog 56, 56. Each locking dog is pivotally secured, intermediate its ends, by means of a pivot pin 58, 58, to the angle bar 52, and the upper or locking ends of said dogs 75 are adapted to project through said slots 57, 57 and into the path of movement of said doors 49, 49. The depending marginal flange 45 of the false bottom plate 43 is provided at each side thereof with outwardly 80 projecting lugs 59, 59, one for each locking dog 56, 56. As shown in the drawings, said lugs 59, 59 extend beneath the tail ends of said locking dogs 56, 56, and, when the forward end of the plate 43 is moved upward 85 by the spring 48, the tail ends of said dogs 56, 56 are also moved upward, thereby rocking the dogs 56, 56 and swinging the locking ends thereof down into the slots 57, 57 and out of the path of movement of the swinging doors 49, 49. In Fig. 9, the locking dogs 56, 56 are shown in unlocked position in full lines and in locked position in dotted lines. When an article is placed within the chamber 16 by forcing the same through the 90 double doors 49, 49, the article rests upon the false bottom plate 43, and, by reason of its weight, depresses the forward margin of the bottom plate 43 downwardly. In the downward movement of the bottom plate 100 43, the lugs 59, 59 are moved downward, thereby permitting the locking dogs 56, 56 to rock and cause the locking ends thereof to project above the horizontal flange 54 and occupy positions to the rear of said doors 105 and in the path of movement of the same. In such position of the parts, the dogs 56, 56 lock the doors 49, 49 against inward movement, and consequently lock the same in closed position. Access, therefore, cannot 110 be had to the chamber 16 through the entrance opening 20. The rear faces of the locking or upper ends of said dogs 56, 56 are beveled, so that the doors 49, 49 may pass freely thereover in the closing of said doors. The doors 49, 49 are locked in closed 115 position as long as an article or articles remain in the chamber 16 upon the bottom plate 43 thereof. To remove the article or articles from the chamber 16, the rear door 39 is opened and the articles withdrawn from the chamber or compartment 16 through the rear opening 38. Upon the removal of such articles, the spring 48 raises the forward portion of the bottom plate 43 and effects the rocking of the locking dogs 56, 56 into lowered position, thereby unlocking the double doors 49, 49.

120 The collection receptacle herein described and shown is built in the wall of a building 125

to which it is to be applied, and marginal portions of the front wall 11 overlap the front face of the wall 10 about the opening in which the receptacle or box is inserted. 5 A wood or like facing 12^a is applied about the margins of the rear wall 12, as shown in Fig. 2, so as to give a finished and neat appearance to the box from the inside of the wall 10. The rear door 39 swings inwardly 10 into the room of the house or apartment of which the wall 10 forms a part, and the article or articles deposited in the receptacle from the outside thereof may be removed 15 from the receptacle by the occupant or tenant of the house, upon opening the rear door 39 and without leaving the room. The delivery man and milkman deposit their respective articles in the proper compartments of the receptacle through the entrance openings thereof, and continue about their respective duties. With such receptacle in the wall, there is no worry for the tenant or owner, nor are the neighbors called upon to receive parcels and the like. The tenant 20 need not be on hand to receive the parcel when delivered, nor be annoyed when the same is delivered. The locking devices all being located inside of the receptacle, said locking devices cannot be pried open or 25 tampered with, nor the articles removed or stolen from the same from the outside of the house. The rear door 39 being locked from within the house, the door cannot be opened, even when the compartments 16, 17 30 are empty. As soon as the articles are removed from the receptacle by the tenant, the latch mechanism is released and the front door's unlocked, so that the receptacle may be opened to receive other articles on subsequent deliveries. The receptacle and its 35 parts are made of metal, and the device is burglar proof. The slots in the rear marginal flange of each of the bottom plates 30, 43, respectively, open downward, and thereby 40 permit the plates to be removed from the compartment or chamber in which they are inserted, when it is desired to clean the collection receptacle.

A receptacle of the character described 50 may be built into the wall as the latter is being built, or the receptacle may be placed in a wall that has already been built.

It is to be understood that the receptacle herein described and shown may be variously modified and changed as to its details 55 of construction and arrangement of parts, without departing from the spirit and scope of our invention, and we do not wish to be limited to the exact details of construction 60 shown and described, except as pointed out in the annexed claims.

We claim as our invention:

1. A collection receptacle of the character 65 described, comprising a plate located there- 70 in and adapted to support an article de-

posited thereon, means for holding said plate above the bottom of said receptacle and permitting said plate to be depressed under the weight of the article placed thereon, said receptacle being provided in one of its walls with an opening through which the article may be passed in depositing the same in said receptacle, a door for closing said opening, a locking member mounted on said door, said plate being provided with a 75 part adapted, when the receptacle is empty, to occupy a position preventing said locking member from moving into locking position, said part being moved, upon the depression of said plate, into a position permitting said locking member to move by its own weight into locking position and lock said door in closed position, when the latter is closed, 80 said receptacle being provided with a second opening through which the article may 85 be removed from said receptacle, and a door for closing said second opening.

2. A receptacle of the character described, comprising upright marginal and bottom walls, a partition member within said receptacle and dividing the interior space thereof into a plurality of compartments, a plate located in each compartment and adapted to support an article deposited thereon, means for holding each plate above the bottom wall 90 of said receptacle and permitting each plate to be depressed under the weight of the article placed thereon, said receptacle being provided in one of its upright walls with a plurality of openings, one opening into each 95 compartment, a door for closing each opening, a locking member for each compartment, each plate being provided with a part adapted, when the compartment within 100 which the plate is located is empty, to occupy a position preventing said locking member from moving into locking position, and said part being moved with the plate when the latter is depressed, into a position 105 permitting the locking member to move by its own weight into locking position and lock the door of its associated compartment closed, when the latter is moved into its 110 closed position.

3. A collection receptacle of the character 115 described, embracing upright marginal and bottom walls, a plate located in said receptacle and adapted to support the article deposited therein, means for yieldably holding said plate above the bottom wall of said receptacle and permitting said plate to be depressed under the weight of the article placed thereon, said receptacle being provided in one of its upright walls with an opening through which an article may be 120 passed in depositing the same in said receptacle, a door slidably applied against the inner face of said wall for closing said opening, a locking member pivotally mounted on the inner face of said door, an 125

- 3 upright flange located in said receptacle and secured to the bottom wall thereof, said flange being provided with a locking notch, said plate being provided with a lug extending into said notch, said lug occupying a position, when the receptacle is empty, in the upper portion of said notch and preventing said locking member from dropping into said notch when said door is closed, said lug being moved downward in said notch in the depression of said plate under the weight of the article placed thereon and permitting said locking member to drop in said notch when the door is closed, 15 said receptacle being provided with a second opening through which the article deposited in said receptacle may be removed therefrom, and a door for closing said last named opening.
- 20 4. A collection receptacle of the character described, embracing upright marginal and bottom walls, a plate located in said receptacle and adapted to support the article deposited therein, means yieldably holding said plate above the bottom wall of said receptacle and permitting said plate to be depressed under the weight of the article placed thereon, said receptacle being provided in one of its upright walls with an 25 opening through which an article may be passed in placing the same in said receptacle, a door slidably applied against the rear face of said wall for closing said open-
- ing, a locking member pivotally mounted on said door, an upright flange secured to said bottom wall and extending longitudinally of said receptacle, said locking member bearing on said flange endwise of said door, said flange being provided with a locking notch adapted to receive the lower end of said locking member when the door is in closed position, said plate being provided with a lug extending into said locking notch and adapted to prevent said locking member from dropping into said locking notch when said receptacle is empty, said lug being moved downward upon the depression of the plate under the weight of the article placed thereon and occupying a position permitting said locking member to enter said locking notch when the door is closed, said receptacle being provided with an opening through which the article deposited in said receptacle may be removed therefrom, and a door for closing said second opening.
- 25 In testimony, that we claim the foregoing as our invention, we affix our signatures in the presence of two witnesses, this 23rd day of February A. D. 1915.
